UNITED STATES PATENT OFFICE.

PAUL MACGAHAN, OF PITTSBURGH, PENNSYLVANIA, ASSIGNOR TO WESTINGHOUSE ELECTRIC AND MANUFACTURING COMPANY, A CORPORATION OF PENNSYLVANIA.

CONTACT MEMBER.

1,358,765.

Specification of Letters Patent. Patented Nov. 16, 1920.

Application filed August 9, 1916. Serial No. 113,957.

To all whom it may concern:

Be it known that I, PAUL MACGAHAN, a citizen of the United States, and a resident of Pittsburgh, in the county of Allegheny and State of Pennsylvania, have invented a new and useful Improvement in Contact Members, of which the following is a specification.

My invention relates to contact members and particularly to non-vibrating contact members for relays and other similar devices.

The object of my invention is to provide a contact member that is so insulated from shocks and jars that the vibration of the device to which it is connected will not be transmitted to its contact piece or button.

It is a well known fact that the armatures of alternating-current relays frequently vibrate due to the alternations of the current and that these vibrations are usually transmitted to the contact members, thereby causing them to become pitted and burned and sometimes causing the apparatus that is adapted to be controlled by the relays to function improperly. In view of the above, I provide a contact member comprising a supporting arm that is mounted on the shaft of the relay. A contact button is adapted to be disposed in an opening in the supporting arm, and a felt member is adapted to so support the contact button out of engagement with the supporting arm that the vibrations of the supporting arm will not be transmitted to the contact button.

Figure 1 of the accompanying drawings is a view, mainly in perspective but partially in section, of an electro-responsive device embodying my invention, Fig. 2 is an elevational view of a contact member embodying my invention, and Fig. 3 is a view, partially in plan and partially in section, of the contact member shown in Fig. 1 of the drawings.

A typical device, in connection with which my invention may be employed, comprises a relay 1 having a magnetizable core member 2, windings 3 and 4, a disk armature 5 that is mounted on a shaft 6, and a control spring 7. A movable contact member 8 is mounted on the shaft 6 and is adapted to engage a resiliently-mounted contact member 9.

The contact member 8 comprises a supporting arm 10 having an enlarged outer

portion with an opening 11 therein. A shock-absorbing flexible member 13, constructed of felt or other similar non-vibratory substance, is secured to the enlarged portion of the arm 10 adjacent the opening 11 by rivets. However, it may be secured thereto by sewing or by cementing with equally good results. A contact button 12 is secured to the member 13 at a point removed from the supporting member 10. A flexible conductor 14 is connected to the button 12 and also to one end of the control spring 7 for the purpose of conducting the current to the contact button 12.

With such a construction, if the armature 70 vibrates, because of the alternations of the current that traverses the windings 3 and 4, the vibrations of the armature 5 will not be transmitted to the contact button 12 because the felt member 13 serves as an insulator to shocks and jars.

I do not limit my invention to the particular structure illustrated or to the particular adaptation herein shown, as it may be variously modified within the spirit and scope of the appended claims.

I claim as my invention:

1. A contact member comprising a supporting member having an opening therein, a flexible felt member disposed in the opening in the supporting member and a conducting member mounted on the felt member out of engagement with the supporting member.

2. A contact device comprising a substantially rigid supporting member having an opening therein, an oscillation absorbing member supported thereby and disposed adjacent the opening in the supporting member, and a conducting member mounted on said absorbing member within the opening in the supporting member.

3. A contact device comprising a supporting member, a contact button, and a suspended felt member connecting the contact button and the supporting member to prevent the transmission of vibrations from the supporting member to the contact button.

4. A contact device comprising a supporting member, a flexible felt member attached thereto, and a contact member suspended on said felt member to prevent the transmission of vibrations from the supporting member to the contact member.

5. A contact device comprising a supporting member, a relatively flat felt member supported at its edges by the supporting member, and a contact member suspended at 5 an intermediate position on said felt member in order that the vibrations of the supporting member shall not be transmitted to said contact member.
6. A contact device comprising a supporting member, a contact button, and a flexible textile fabric suspended from the supporting member and supporting the contact button.
7. A contact member comprising a supporting member having an opening therein, 15 and a contact button disposed in the opening and

a shock-absorbing felt insulator disposed between the supporting member and the contact button.

8. A contact member comprising a supporting member having an opening therein, a contact button disposed in the opening, a shock-absorbing felt member disposed between the supporting member and the contact button and a flexible conducting member 20 for electrically connecting the contact button to the supporting member.

In testimony whereof, I have hereunto subscribed my name this 20th day of July, 1916.

PAUL MacGAHAN.
